VAPORIZING TYPE OIL BURNER

John W. Miller and Frederick T. Stoney, Lansing, Mich., assignors to Motor Wheel Corporation, Lansing, Mich., a corporation of Michigan

Application November 30, 1953, Serial No. 394,934

17 Claims. (Cl. 158—91)

This invention relates to vaporizing type oil burners and more particularly to a burner structure for stabilizing and improving the combustion in the burner at the pilot fire stage of operation.

In vaporizing pot type burners one of the problems that arises is the inevitable production of eddy currents. When the burner is operating at pilot fire, vertical air currents in the burner result from the temperature differential in the burner and in turn produce horizontal cross currents which are both radial and circumferential. These eddy currents, both vertical and horizontal, tend to produce unstable combustion and also tend to extinguish the pilot flame so that it becomes necessary to increase the minimum amount of fuel admitted to the burner at pilot operation to maintain combustion. Pilot flame stabilizers, that is, burner arrangements for producing a stable and clean pilot flame, have heretofore been proposed which remedy this problem to some extent. For example, in the Miller et al. Patent 2,448,148 there is disclosed a pilot stabilizer which tends to confine the burning at the fuel inlet opening. Experience has shown that although the arrangement shown in said Miller et al. patent tends to stabilize the flame at pilot operation, nevertheless, the combustion at pilot fire operation with such an arrangement is sometimes inefficient and tends to produce a smoky flame.

It is an object of this invention to improve upon the arrangement shown in said Miller et al. patent and more specifically it is an object to advantageously utilize the eddy currents naturally occurring in the burner for the purpose of improving combustion at pilot fire stage of operation.

In the drawings:

Fig. 1 is a fragmentary vertical sectional view of a burner embodying the present invention.

Fig. 2 is a perspective view of one of the shield members of the pilot fire stabilizing structure.

Fig. 3 is a perspective view of the other shield member of the pilot fire stabilizing structure.

Fig. 4 is a sectional view along the line 4—4 of Fig. 1.

Fig. 5 is a fragmentary sectional view of a burner embodying a modified form of pilot fire stabilizer structure of this invention.

Fig. 6 is a sectional view along the line 6—6 of Fig. 5.

Fig. 7 is a fragmentary sectional view of a burner showing another modified form of pilot fire stabilizer of this invention.

Fig. 8 is a sectional view along the line 8—8 of Fig. 7.

Figs. 9, 10 and 11 are perspective views of the pilot stabilizer arrangements shown in Figs. 1, 5 and 7, respectively.

Referring to the drawings, there is shown in Fig. 1 a heating structure which includes a pot type oil burner generally designated 10. The burner 10 includes a cup shaped bottom wall portion 12 which is flanged around its upper edge to telescopically receive a tubular side wall member 14. Adjacent its upper end, side wall 14 is provided with a circumferential bead 16 which has

2

a close fit with a casing 18 which defines in the space above burner 10 a combustion chamber 20. The side wall 14 of the burner is provided with a plurality of air inlet openings 22. The openings 22 are circumferentially spaced and preferably arranged in vertically spaced rows as indicated. An inclined baffle 24 is arranged within the burner. Baffle 24 is provided with a central opening 26 and divides the burner into an upper chamber 28 and a lower chamber 30. It will be observed that some of the air inlet openings 22 communicate with chamber 30 and others of the openings 22 communicate with the chamber 28. At its upper end burner 10 is provided with a centrally apertured top wall 32 on which is positioned an anti-explosion baffle 34. The side wall 14 of the burner is also provided with inlet openings 36 and 38 for the admission of secondary air above the plane of top wall 32. Fuel is admitted to the burner through an inlet pipe 40 and an inlet opening 42 at one side of the burner adjacent the bottom wall 12. Immediately adjacent the inlet opening 42 the bottom wall 12 of the burner is provided with a recess or pocket 44 which is arranged to fill with oil before the oil flows over the bottom wall 12 of the burner.

The improvement of the present invention resides in the provision of an arrangement for producing a clean, stable flame adjacent the inlet opening 42 when fuel is being admitted to the burner in a minimum amount corresponding to pilot fire operation. The structure provided for this purpose may take several forms, the preferred structure being shown in Figs. 1 through 4. The pilot stabilizer of preferred construction comprises two shield members 46 and 48. The member 46 is fashioned with two generally converging baffles or side walls 50, the upper edges of which are connected by a top wall 52. The member 46 is also provided with a rear wall 54 which is arcuately shaped in horizontal section to conform with the contour of the cylindrical wall portion 56 of the cup shaped member 12 of the burner. The rear wall 54 of member 46 is provided with a central opening 58 at its lower edge which is adapted to register with the inlet opening 42 when the shield 46 is positioned in the burner as shown in Fig. 1.

The member 48 of the pilot stabilizer includes a pair of upstanding baffles 60, the upper edges of which are spanned by a top wall 62. Top wall 62 has a rear arcuate edge 64 which conforms with the curvature of side wall 14 of the burner at the portion thereof adjacent inlet opening 42 just below the inclined baffle 24. Top wall 62 is preferably inclined relative to the lower edges of upstanding baffles 60 and the baffles 60 are dimensioned in height such that the member 48 may be slipped into position in the burner with the baffles 60 supported on the bottom wall 12 of the burner and the top wall 62 fitting flush against the underside of baffle 24. It will be observed that the depth of top wall 62 in a radial direction or a direction from front to back is greater than the depth of the baffles 60 in the same direction. Therefore, as shown more clearly in Fig. 4, when the member 48 is positioned within the burner with the top wall 62 underlying baffle 24 and with the edge 64 thereof engaging the side wall of the burner, the baffles 60 are spaced radially inwardly from the side wall of the burner. It will also be noted that top wall 62 and baffles 60 extend radially inwardly beyond top wall 52 and side walls 50 of shield member 46.

On its bottom side, top wall 62 is provided with a centrally arranged, vertically depending lug or wall 66 which extends from the straight edge 68 to the arcuate edge 64. The top wall 52 of member 46 is provided with a notch 70 at its inner edge in which a projection 72 at the lower end of lug 66 is arranged to engage to hold the member 46 in operative relation with the member 48 when in the burner.

It will be observed that in the operative position of members 46 and 48, the chamber 74, defined by the walls 50, 52 and 54 of member 46 and the bottom wall 12 of the burner, has an opening 75 at its radial inner or front end. Furthermore, the walls 50 cooperate with the baffles 60 to provide radial passageways 76, the outer or rear ends of which communicate with the burner through the spaces 78 between the rear vertical edges of the baffles 60 and the side wall 14 of the burner. The inner or front ends of passageways 76 communicate with the burner through the openings 79. The wall 66 of member 48 forms a radially arranged central partition extending vertically between the top walls 52 and 62. At its outer vertical edge, wall 66 is shaped to interfit the side wall 14 of the burner.

The operation of the burner provided with the pilot stabilizer arrangement described above is as follows: Fuel flows into the burner through the inlet pipe 40 and through openings 42 and 58 and into the oil pocket 44. The oil pocket 44 is shielded from the burner by the member 46 so that communication between the interior of the burner and the oil pocket 44 is established only through the open inner end 75 of the shield 46. The member 46 thus forms the shielded chamber 74 in which the oil in pocket 44, after being ignited, is vaporized. The heat of combustion induces vertical air currents in the burner which in turn produce a flow of air across the bottom wall 12 of the burner and into chamber 74. This current of air, which is represented by the arrows 80 in Fig. 1, mixes with the oil vapors in chamber 74, thereby forming a very rich mixture of air-oil vapors which flows out of the chamber 74 along the upper edge of opening 75. The air which mixes with the vapors in chamber 74 is of insufficient amount to form a burning mixture and these rich vapors are diluted by the currents of air flowing radially inwardly on either side of partition 66 to provide a combustible mixture which burns along the upper edge of opening 75 of chamber 74. This additional air flows into the space between walls 52 and 62 through the openings 22 in that portion of the side wall 14 of the burner that extends between these two vertically spaced walls. As the amount of fuel admitted to the burner is increased, the heat generated in the burner likewise increases and the vertical and horizontal eddy currents of air are also increased. The air that circulates horizontally in the burner enters the passageways 76 through the openings 78 and flows radially inwardly toward the center of the burner. This flow of air through the passageways 76 tends to draw oil vapors out of mixing chamber 74 and mixes therewith to initiate burning also at the openings 79 at the inner ends of passageways 76. With a further increase in the amount of fuel admitted the flame gradually moves out into the burner and the bottom of the burner is filled with flame. The flame gradually moves upwardly in the burner as the rate of fuel admission is increased until at high fire stages of combustion burning takes place in combustion chamber 20.

In a typical construction with a burner having a diameter of about twelve inches with the shield member 46 being about one and three-quarter inches high and two and one-half inches wide at its front or inner end, and with shield 48 being about three and one-half inches high and about three and three-eighths inches wide at its front end, the side baffles 60 being spaced about one-half inch inwardly from the side wall 14 of the burner, a flame along the upper edge of opening 75 is initiated at a flow of about 60 cc. per hour which is considered pilot fire. At a flow of about 85 cc. per hour the circumferential air currents moving through spaces 78 and then radially inwardly through passageways 76 pick up enough oil vapor as they flow past the opening 75 to start burning at the openings 79 also. The flame tends to stay at the openings 79 and along the upper edge of the opening 75 until a flow of about 180 cc. per hour is reached when it moves out into the burner, as explained above.

In Figs. 5 and 6 there is shown a simplified form of pilot stabilizer construction. In this arrangement the use of two shield members, such as shown at 46 and 48 of the previous embodiment described, is avoided; and in place thereof, a single shield member 82 is employed. The member 82 is preferably fashioned as a casting having two sets of side wall baffles 84 and 86 and an inclined top wall 88. The side wall baffles 84 and 86 are dimensioned in height so that when shield member 82 is in the operative position within the burner, top wall 88 fits flush beneath inclined baffle 24 within the burner. Top wall 88 has a substantially straight front or inner edge 90 and an arcuate rear or outer edge 92 which interfits with the arcuate side wall 14 of the burner. The side wall baffles 84 are arranged to extend generally radially inwardly from the side wall 14 of the burner whereas the side wall baffles 86 are spaced radially inwardly from the side wall 14 of the burner to provide openings 94 for radial passageways 96 which discharge into the burner at their inner ends through openings 98.

The arrangement shown in Figs. 5 and 6 operates generally the same as that shown in Figs. 1 through 4. However, since the openings 22 in the side wall of the burner communicate directly with the mixing chamber 98 which is defined by the bottom and side walls 14 and 16 of the burner and the walls 84 and 88 of the shield members 82, burning takes place within the chamber 98 at a relatively low rate of fuel admission and the flame gradually moves out to the openings 96 as the rate of fuel admission is increased.

In Figs. 7 and 8 there is shown another modified form of pilot stabilizer construction of this invention. This form of construction differs from that shown in Figs. 5 and 6 primarily in that the single shield member 100 is of less height than shield member 82 (Fig. 5) and the top wall 102 thereof is flat rather than inclined. Also in the arrangement shown in Figs. 7 and 8, the two inner radially extending side walls 104 are spanned across their rear vertical edges by a rear wall 106. The other two radially extending side walls 108 are spaced radially inwardly of the side wall 14 of the burner to provide inlet openings 110 to the radial passageways 112 which communicate with the burner at their inner ends through the openings 114. The shield member 100 is retained in position by means of a lug 116 depending from the lower side of baffle 24 and having a projection 118 at the lower end thereof which engages in a slot 120 formed in the front edge of the top wall 102.

In operation the form of construction shown in Figs. 7 and 8 is generally the same as that shown in Figs. 1 through 4. It will be observed that the mixing chamber 122 is open only at its front or inner end. Thus, as is the case with the form of construction shown in Figs. 1 and 4, insufficient air is admitted to the chamber 122 to form a burning mixture within the chamber and the flame is initiated along the inner edge of top wall 102. The reason for the initiation of combustion at this point rather than within the chamber 122, as is the case with the arrangement shown in Figs. 5 and 6, is twofold. In the first place, chamber 122 is of substantially less height than the chamber 98. This prevents the radial air currents from penetrating all the way into chamber 122. Also, since the air inlet openings 22 in the side wall 14 of the burner are disposed above top wall 102 and the rear wall 106 prevents leakage of air into chamber 122 from the rear side thereof, insufficient air enters chamber 122 to form a combustible mixture. Thus, at low rates of fuel admission the flame is initiated along the inner edge of wall 102 and when the fuel is admitted at a higher rate the circumferential air currents produced by the greater temperature differential in the burner flow radially inwardly through passageways 112 and pick up enough oil vapor to start burning also at the openings 114.

Thus, it will be seen that we have provided a pilot fire

stabilizing structure in a vaporizing pot type burner which is designed to actually utilize the eddy currents produced in the burner advantageously for the purpose of stabilizing and improving the combustion at pilot fire stages of operation.

We claim:

1. In a vaporizing pot type burner having a bottom wall, a tubular side wall provided with circumferentially spaced air inlet openings and a fuel inlet opening at one side of said burner adjacent said bottom wall, means for improving combustion in said burner at pilot fire stage or operation comprising, means within the burner and cooperating with the bottom wall thereof to define a relatively small chamber in the burner which extends radially inwardly from the side wall of the burner and is in open communication with the burner at its radially inner end, said chamber being located so that said fuel inlet opens thereto and being generally impervious except for said open end thereof, said chamber having a radially extending side wall defining, at least in part, the open end of the chamber, a radially extending wall in said burner closely spaced from and cooperating with said side wall of the chamber to form a radially inwardly extending passageway communicating with the interior of the burner at its radially outer end adjacent the side wall of the burner and at its radially inner end adjacent the open end of said chamber.

2. The combination set forth in claim 1 wherein said chamber has a top wall extending generally horizontally and radially inwardly from the side wall of the burner and including another wall in said burner extending generally horizontally and radially inwardly from the side wall of the burner, said last mentioned wall being spaced above and adjacent said top wall of said chamber, at least some of said air inlet openings in the burner side wall being located at the portion of said burner side wall extending between said two generally horizontally extending walls.

3. In a vaporizing pot type burner having a bottom wall, a tubular side wall provided with circumferentially spaced air inlet openings and a fuel inlet opening at one side of said burner adjacent said bottom wall, means for improving combustion in said burner at pilot fire stage of operation comprising, means including a pair of side walls and a top wall cooperating with the bottom wall of the burner to define a relatively small chamber in said burner adjacent the burner side wall, said chamber being located so that said fuel inlet opens thereto, said side walls extending generally radially inwardly from the burner side wall and said top wall extending between and connecting the upper edges of said side walls, the radially inner end of said chamber being in open communication with the interior of said burner and a pair of generally radially extending baffles positioned exteriorly of said chamber one adjacent to and spaced from each of said side walls of said chamber, said baffles cooperating with said side walls of said chamber to form generally radially extending passageways along opposite sides of said chamber, said passageways communicating with the interior of the burner adjacent their radially outer ends adjacent the side wall of the burner and at their radially inner ends adjacent said open end of said chamber, said baffles extending

radially inwardly a greater extent than said side walls of said chamber.

4. The combination set forth in claim 3 wherein said side walls of said chamber and said baffles are disposed 5 in converging, non-intersecting relation.

5. The combination set forth in claim 3 wherein said baffles are spaced from the burner side wall.

6. The combination set forth in claim 3 wherein the outer edges of said side walls are in close engagement 10 with the side wall of the burner, the portion of said burner side wall extending between said last mentioned edges providing a wall at the radially outer end of said chamber.

7. The combination set forth in claim 3 wherein said 15 chamber includes a rear wall connecting the radially outer end of the chamber side walls and extending upwardly from substantially the lower edges of said side walls to said top wall.

8. The combination set forth in claim 3 wherein said 20 top wall connects with the upper ends of said baffles.

9. The combination set forth in claim 3 wherein some of said air inlet openings communicate directly with said chamber.

10. The combination set forth in claim 3 including a 25 generally horizontal wall extending radially inwardly from the burner side wall and spaced above said top wall.

11. The combination set forth in claim 10 wherein said 30 air inlet openings are disposed exclusively above the plane of said top wall.

12. The combination set forth in claim 10 including a vertical partition extending radially between said last two mentioned walls along a line generally centrally of said top wall.

35 13. The combination set forth in claim 10 including a vertical partition extending radially inwardly from the burner side wall between said top wall and said generally horizontal wall along a line extending generally centrally of said top wall.

40 14. The combination set forth in claim 10 wherein said top wall connects with the upper ends of said baffles.

15. The combination set forth in claim 10 wherein said generally horizontal wall extends between and connects the upper ends of said baffles.

45 16. The combination set forth in claim 10 wherein said generally horizontal wall extends radially inwardly beyond said top wall.

17. The combination set forth in claim 10 including a 50 depending partition on said horizontally extending wall, said partition extending radially inwardly from the side wall of the burner, the lower end of said partition and said top wall being provided with interengaged lug and socket members.
